United States Patent Office

Des. 182,266
Patented Mar. 11, 1958

182,266

CHARCOAL GRILL OR SIMILAR ARTICLE

Leo E. Alexander, Alamo, Calif.

Application May 20, 1957, Serial No. 46,248

Term of patent 3½ years

(Cl. D81—10)

Fig. 1.

Fig. 4.

Fig. 2.

Fig. 3.

Figure 1 is a perspective view of a charcoal grill showing my new design;

Figure 2 is a side elevational view of the grill taken from left of Figure 1;

Figure 3 is an end view thereof, both ends being the same in appearance; and

Figure 4 is a plan view thereof.

I claim:

The ornamental design for charcoal grill or similar article, as shown and described.

References Cited in the file of this patent

UNITED STATES PATENTS

D. 172,672 Lennox ----- July 20, 1954

FOREIGN PATENTS

83,150 Germany ----- Apr. 24, 1894

OTHER REFERENCES

Haeger Pottery Catalog, received March 29, 1950, sec. 4, page 4, item R-725.

Haeger Pottery Catalog, received November 9, 1955, page 3, item R-958 and item R-252.